United States Patent Office

Des. 210,744
Patented Apr. 9, 1968

210,744

LAMP POST

Hugh Major McKittrick, Middletown, N.J.
(80 Rufledge Drive, Red Bank, N.J. 07701)

Filed Mar. 17, 1966, Ser. No. 1,522

Term of patent 7 years

(Cl. D48—31)

The single figure is a side elevation of a lamp post showing my new design, the side opposite that shown being a mirror image of the side shown.

I claim:

The ornamental design for a lamp post, as shown and described.
